UNITED STATES PATENT OFFICE.

PURCELL THOMAS WEBB, OF CHRISTCHURCH, NEW ZEALAND.

SAFETY DEVICE FOR RAILWAYS AND THE LIKE.

Application filed April 24, 1925, Serial No. 25,629, and in New Zealand May 2, 1924.

This invention relates to devices used in connection with railway lines for the purpose of indicating to the drivers of approaching trains, the presence of slips or other obstructions on the line, and has for its object the provision of improved means for the aforesaid purpose.

The invention consists in providing at a place on a railway line where a slip is thought likely to occur, a fence barrier, or line at one or both sides of the railway line, at a suitable height from the ground, and forming part of an electric circuit, containing safety lamps situated near the ends of the section of railway line so dealt with or protected, the lamps under normal conditions remaining alight.

Should a slip occur, the protecting fence barrier or line will be broken, and the lamps be extinguished, so that the driver of a train failing to observe a safety light, on approaching a section of railway line so dealt with or protected, will be warned that an inspection of the protected section of railway line should be made, before running the train over same.

In a further form the invention consists in providing at a place on the railway line where a slip is likely to occur, an insulated section of railway line, the rails of said insulated section forming part of an electric circuit adapted to be closed by the presence on said insulated section, of a train, the wheels and axles of which bridge the rails and complete the circuit. Included in said circuit is or are one or more protecting fences barriers or lines at one or both sides of the line as aforesaid, and also distinctively coloured lights, and or sound or other signals, so that upon a train running on to said insulated section of railway line when same is clear, the circuit will be completed and signals either visual or by sound, or both, will be given, indicating to the driver that he may proceed over said protected section of line. Also in order to warn the driver of the approach of the train to a protected section of railway line a further electric circuit is provided the latter containing lights or other signals located near the ends of the said insulated section of railway line.

In addition to or instead of the protected section indicating lights near the ends of said section, mechanically operated gongs or the like adapted to be operated by the train

may be provided to give warning of the train's approach to said section.

In the accompanying drawing in conjunction with which the invention will be further described.

Figures 1 to 3 are diagrammatic views illustrating different forms of the invention.

In the arrangement shown in Figure 1, the section 2 of railway line, is insulated at 6 from the remainder of the railway line, the rails of said insulated section 2, being also included in the same circuit as the line fence or barrier 1, and the lamps 4, so that the circuit will be closed by the wheels and axles of a train running upon said section 2. In 70 this form a gong 5 or the like is also used to give warning of the train's entrance or approach to said insulated section 2 and should the lamp 4 at or near the entrance end of the latter, fail to light, upon the train bridging the rails of the insulated section 2 of railway line, it is an indication that the line fence or barrier 1 is broken and the line should be inspected, before the train proceeds thereover.

The arrangement shown in Figure 2 is similar to that shown in Figure 1, except that instead of current being drawn from overhead wires 3 it is drawn from a local source of supply such as battery 7.

In the arrangement shown in Figure 3 there is provided at each end of a section 2 of railway line a lamp 8, the latter being used instead of, or in addition to the gong 5 or other alarm sounding means employed, 90 for the purpose of indicating that a protected section of line is being entered upon or approached.

The lamps 8 are supplied with current from the overhead wires 3, and are constantly alight, while the lamps 4 are adapted to be illuminated only upon the line being clear, and through the closing of the circuit in which they are located, by the train wheels bridging the rails of the insulated section 2.

Other modifications of the invention, may be devised without departing from the spirit of the invention.

What I do claim and desire to obtain 105 by Letters Patent of the United States of America is:—

1. Means for the purpose specified, comprising an electric line erected adjacent a section of railway line to be protected, and 110

2
forming part of an electric circuit containing lamps, located near the ends of said section of railway line, said lamps being adapted to be extinguished by a fall of earth or 5 the like breaking said electric line; and signaling means for giving warning of the approach of a train, to said section of railway line, the section of railway line protected by the electric line being insulated from the 10 rest of the railway line and also forming part of the circuit through the electric line and the lamps, and the said circuit being closed when the electric line is unbroken by the wheels and axle of a train bridging 15 the rails of said insulated section of railway line, substantially as described.

2. Means for the purpose specified, according to claim 1, wherein the means for giving

warning of the approach of a train to the protected section of railway line 20 comprise gongs, actuated by the train, substantially as described.

3. Means for the purpose specified according to claim 1 wherein constantly illuminated lamps are located near the ends of the protected section of railway line, for indicating the location of the protected section of railway line, substantially as described. 25

4. Means for the purpose specified, according to claim 1, wherein the electric line 30 erected adjacent the railway line, comprises a wire fence, substantially as described and illustrated.

In testimony whereof I affix my signature.

PURCELL THOMAS WEBB.
